RING

Joseph W. Grant, Wakefield, Mass.

Application April 16, 1951, Serial No. 14,859

Term of patent 14 years

(Cl. D45—10)

To all whom it may concern:

Be it known that I, Joseph W. Grant, a citizen of the United States, residing in the city of Wakefield, county of Middlesex, State of Massachusetts, have invented a new, original, and ornamental Design for Rings, of which the following is a specification, reference being had to the accompanying drawing, forming part hereof, and in which,

Figure 1 is a plan view of the ring;

Figure 2 is a side elevation; and

Figures 3 and 4 are edge elevations, respectively, from opposite points of view.

I claim:

The ornamental design for a ring, as shown.

JOSEPH W. GRANT,
